UNITED STATES PATENT OFFICE

EDWIN F. BRITTEN, JR., OF MAPLEWOOD, NEW JERSEY, ASSIGNOR TO MONROE CALCULATING MACHINE COMPANY, OF ORANGE, NEW JERSEY, A CORPORATION OF DELAWARE

ATTACHMENT FOR CALCULATING MACHINES

Application filed August 15, 1929. Serial No. 386,050.

This invention relates to calculating machines, and particularly to calculating machines having transversely and vertically movable carriages.

5 The principal object is to put a tension on the carriage moving element so as to insure smooth and substantially noiseless shifting of the carriage.

10 Another object is to produce a device of this nature automatically called into action when the machine is set for full automatic division.

15 Another object is to produce a device of this nature which may be slightly modified so as to place a constant tension on the carriage moving member.

20 Another object is to provide a device of this nature with means whereby the tension may be increased and decreased so as to compensate for the weight of different styles of carriage.

25 With these and other objects in view which will become apparent as the specification proceeds, the invention resides in certain novel construction and combination and arrangement of parts, the essential features of which are shown in the accompanying drawings, in which:

30 Fig. 1 is a top plan view of a calculating machine provided with my improvement.

Fig. 2 is a vertical sectional view taken substantially on line 2—2 of Fig. 1.

35 Fig. 3 is a detail top plan view of the essential elements of the invention per se in ineffective position.

Fig. 4 is a similar view showing the parts in effective position.

Fig. 5 is a detail vertical sectional view on line 5—5 of Fig. 3.

40 Figs. 6 and 7 are detail sectional views on lines 6—6 and 7—7 of Fig. 1.

45 Figs. 8 and 9 are enlarged detail horizontal sections taken immediately above the eccentric portion of the pivot pin and indicating respectively the lowest and highest tension positions of the eccentric.

Like characters of reference refer to like parts in all views.

50 Referring to the drawings in detail, 10 represents the casing and 11 the framework

of a calculating machine. By way of illustrating the application of my invention, I have chosen to show the same as incorporated in a calculating machine of the well-known Monroe construction, although this is to be 55 considered as merely illustrative, the invention being applicable to machines of various types. The controlling, actuating and clearing mechanism for the Monroe type of machine is fully set forth in the U. S. patent to 60 G. C. Chase No. 1,566,650, and the pending application of E. F. Britten, Jr. Ser. No. 387,073, filed Feb. 2, 1929, and disclosures therein referred to, to all of which reference may be had for a complete disclosure of such 65 mechanism.

The keyboard frame is shown at 12 and guides a plurality of manipulative members as follows: digit setting keys 13, zero keys 14, keyboard clearing key 15, repeat key 16, 70 non-repeat key 17, add operating key or plus bar 18, subtract operating key or minus bar 19, division lever 20, counter rotation-reversing shift lever 21, and multiplying keys 22. A driving motor is shown at 23, a hand operating crank at 24, and a carriage at 25. The carriage 25 carries a plurality of accumulators 26 and two sets of counters indicated at 27 and 28, the counters 27 being of the "nineteen point" type (having no carry- 75 mechanism and each bearing the nine significant digits running in reverse directions from a common zero, one set of significant digits being colored differently from the other), and the counters 28 being of the usual 80 "ten-point" type with carry mechanism.

The direction of rotation of the accumulators and counters 26, 27, and 28 is controlled by the manipulative members 18, 19, 20 and 21, the latter serving merely to reverse driving of the counters and not of the accumulators.

Briefly, amounts set up in the digit setting keys 13, and thereby on differential actuating gears 29 (Fig. 2) are registered upon the differential registration wheels or accumulators 26 by the operation of differential gear shaft 30 and of shaft 31 whereon the tension-carry members are mounted, these shafts being connected by 1—1 ratio gears and ellipti- 95 100

cal gears (not shown). Power is derived from the motor 23 for rotating this mechanism, but the hand crank 24 may be retained as an alternative means of operation. 5 Rotation of the differential actuating gears 29 effects registration on the accumulators 26 according to the setting of the digit keys 13, and each operation of the machine causes 10 a rotation of one digit space of one counter of each of the sets 27 and 28, the denominational counter operated being controlled by the position of the carriage.

As described in said application rotation of a clearing handle indicated herein at 32 may 15 be utilized to clear either the accumulators or counters. If the handle 32 is turned in a clockwise direction as viewed from the right hand side of the machine it will effect the clearing of the counters 27 and 28, while rotation of the handle 32 in a counter-clockwise direction as viewed from the right-hand side of the machine will effect clearing of the accumulators 26.

The carriage 25 is movable horizontally 20 by means of a handle 33 mounted on the front end of a shaft 34 running from front to rear of the keyboard 12. Shaft 34 carries a cross member 35 having rollers 36 adapted to engage teeth on the carriage so as to raise the carriage, shift it horizontally, and control the dropping back of the carriage, as is well known in the art. The shaft 34 may also be operable automatically during division, by means already well known and on the market. During such automatic shifting, 25 the shaft is given a quick impulse and consequently the carriage comes to its new position with considerable noise and jar. The present invention contemplates minimizing 30 of such noise and jar.

Pinned or otherwise secured to shaft 34 is a collar 37 which rotates with the shaft. The keyboard 12 is cut away to permit a portion of collar 37 to extend therethrough. In rear 45 of collar 37 is a friction disk 38 which also extends thru the keyboard, but which is free on shaft 34 and prevented from turning therewith by fingers 39 of the keyboard 12 extending into notches 40 of disk 38. Coiled 50 about shaft 34 in rear of disk 38 is a tension spring 41 which is of somewhat larger inside diameter than the outside diameter of shaft 34, so that the spring is free on the shaft. A disk 42 is free on shaft 34 in rear of spring 41.

55 A lever 43 of L-shaped formation is formed with a pair of fingers 44 and 45, the finger 45 being riveted to the lever proper at 46. These fingers are bent so as to embrace shaft 34 in rear of washer or disk 42, finger 44 being above the shaft and finger 45 below the same. The fingers 44 and 45 have a slot 47 formed in them thru which an eccentric pivot pin 48 passes. The pin 48 passes thru the keyboard and its eccentric portion 49 forms 60 the pivot for lever 43. By turning pin 48

its eccentric portion 49 may be positioned forwardly or rearwardly so that rocking of lever 43 may tension spring 41 to a greater or less extent. This feature is included so as to obtain the proper amount of tension to accommodate different types of carriage,—for it will be recalled that carriages in the Monroe type of machine vary in length, and consequently in weight, in accordance with the denominational capacity. The slots 47 in 75 the members 44 and 45 are elongated cross-wise of the keyboard so as to permit the necessary movement of the eccentric 49 without effecting any cross-wise movement of lever 43. 80

An arm 50 of lever 43 extends forwardly at their left-hand portion of the keyboard and is formed with a notch 51 which embraces the division lever 20. The lever 43 is maintained in close relation to the under side of the keyboard by a headed pin or screw 52, the shank of which passes thru a slot 53 in arm 50 and is secured in the keyboard frame 12. 85

It is now apparent that when the division lever 20 is moved into its rearmost or effective position, the lever 43 will be rotated clockwise as viewed from the top, thereby causing fingers 44 and 45 to move washer 42 forwardly on shaft 34 and thereby tensioning spring 41 according to the position of eccentric 49. Tensioning of spring 41 causes friction disk 38 to bear against collar 37, thereby causing the carriage to be retarded in its dropping movement just sufficiently to eliminate the 90 jar and minimize the noise. As soon as lever 20 is returned to normal the friction is released for easy manual operation of the carriage moving means. 100

It may be desired in some machines to have 105 the tension permanently applied, as, for instance, in machines used wholly or chiefly for multiplication. Where this is desired, the lever 43 may be cut off along line A—B and a pin inserted at C to hold lever 43 in its effective or tensioning position. In such a machine, the tension is always operative whether the carriage is moved from one denominational position to another automatically or by hand. 110

115 While I have described what I consider to be the most desirable embodiment of my invention, it is obvious that many changes could be made without departing from the spirit of my invention, and I, therefore, do not limit myself to the exact construction shown, or to anything less than the whole of my invention as hereinbefore described, and as hereinafter claimed. 120

125 I claim:

1. In a calculating machine, the combination of calculating mechanism, a transversely movable carriage, means for moving said carriage transversely, a tension device cooperative with said carriage moving means 130

- and adapted to retard operation thereof, and means for automatically rendering said tension device effective and ineffective.
2. In a calculating machine, the combination of a carriage, accumulators mounted on said carriage, means for actuating said accumulators, a controlling device for controlling the character of computation performed by said actuators and accumulators, means for shifting said carriage from one denominational position to another, and means controlled by said device resistance for applying to said carriage shifting means for minimizing the noise and jar incident to the shifting of said carriage.
3. In a calculating machine, the combination of a carriage, accumulators mounted on said carriage, actuating means for driving said accumulators in either direction at will, a device for controlling the direction of drive of said accumulators by said means, means for shifting said carriage from one denominational position to another, and means controlled by said device for automatically applying resistance to said carriage shifting means during rotation of said accumulators in one direction.
4. In a calculating machine, the combination of a carriage, accumulators mounted on said carriage, controlling means associated with said accumulators for performing division, means for shifting said carriage from one denomination to another, and means for automatically applying a brake to said carriage shifting means when the said controlling means is effective.
5. The combination of a carriage, accumulators on said carriage, a shaft operable to effect shifting of said carriage from one denominational position to another, braking means for said shaft, actuating means for said accumulators, and a manipulative member operable to control operation of said accumulators by said actuating means and to simultaneously render said braking means effective.
6. The combination of a carriage, accumulators mounted on said carriage, actuating means for said accumulators, a shaft operable to move said carriage from one denominational position to another, a braking device associated with said shaft, a lever for operating said braking device, and a manipulative element in engagement with said lever and operable for controlling the character of computation to be performed by said accumulators and actuating means and concomitantly operating said lever to effect braking action of said device.

60 In testimony whereof I affix my signature.
EDWIN F. BRITTON, JR.

CERTIFICATE OF CORRECTION.

Patent No. 1,807,192.

Granted May 26, 1931, to

EDWIN F. BRITTON, JR.

It is hereby certified that error appears in the printed specification of the above numbered patent requiring correction as follows: Page 2, line 82, for "their" read the; page 3, line 12, claim 2, for "resistance for applying" read for applying resistance; and that the said Letters Patent should be read with these corrections therein that the same may conform to the record of the case in the Patent Office.

Signed and sealed this 7th day of July, A. D. 1931.

(Seal)
